DESIGN FOR A LIPSTICK CASE

James L. Younghusband, Chicago, Ill.

Application January 10, 1939, Serial No. 82,271

Term of patent 3½ years

To all whom it may concern:

Be it known that I, James L. Younghusband, a citizen of the Dominion of Canada, residing at 11 East Hubbard Street, Chicago, Illinois, have invented a new, original, and ornamental Design for a Lipstick Case, of which the following is a specification, reference being had to the accompanying drawing, forming a part thereof.

Fig. 1 is a front elevational view; Fig. 2 is a perspective view and Fig. 3 a bottom plan view of a lipstick case embodying my new design.

The dominant features of the design reside in the portions shown in full lines.

I claim:

The ornamental design for a lipstick case, substantially as shown and described.

JAMES L. YOUNGHUSBAND.
